WHEELED TOY STEERED BY REMOTE CONTROL

Raymond Lohr and Richard Nelson Carver, Erie,
Pa., assignors to Louis Marx & Company, Inc.,
New York, N. Y., a corporation of New York

Application January 3, 1938, Serial No. 183,070

18 Claims. (Cl. 46—210)

This invention relates to wheeled toys, particularly self-propelled toys, and more especially to such toys arranged for steering by remote control through a light string. The primary object of the invention is to generally improve wheeled toys, particularly by arranging the same to be steered under the control of a person walking along with the toy, so that the toy may be operated in an erratic and amusing manner. If desired, the toy may be made to simulate an animal, say a pet dog with a string extending from a simulated collar, and acting as a leash. This greatly enhances the realism of the toy because the toy runs along under its own power, and may therefore run ahead of the child playing with the same as though it were a live dog. The toy may be steered by a steering wheel normally biased in one direction by a very light spring so that a slight tension on the cord or simulated leash causes the toy to turn in the other direction, and without stopping or interfering with the continued running of the toy along the ground.

Still another object of the invention is to provide the toy with means for fixing the steering of the toy in any desired direction, and to compactly dispose of the control string so that the toy may be operated as an ordinary wheeled toy whenever it is not desired to use the remote control steering feature.

To the accomplishment of the foregoing and other objects which will hereinafter appear, the invention consists in the wheeled toy and driving and steering elements therefor, and their relation one to the other, as hereinafter are more particularly described in the specification and sought to be defined in the claims. The specification is accompanied by drawings in which:

Fig. 1 is a partially sectioned side elevation of a toy automobile embodying features of the invention;

Fig. 2 is a bottom plan view of the forward portion thereof, showing the steering mechanism;

Fig. 3 is a transverse section taken in the plane of the line 3—3 of Fig. 1;

Fig. 4 is a section taken in the plane of the line 4—4 of Fig. 3;

Fig. 5 is a partially sectioned side elevation of a toy simulating a Scottie dog, and embodying features of the invention;

Fig. 6 is a section taken in the plane of the line 6—6 of Fig. 5, and is explanatory of the steering mechanism;

Fig. 7 is a partially sectioned side elevation of

a modified form of toy automobile embodying features of the invention;

Fig. 8 is a horizontal section taken in the plane of the line 8—8 of Fig. 7, and is explanatory of the steering mechanism; and

Fig. 9 is an enlarged section through the steering mechanism taken in the plane of the line 9—9 of Fig. 8.

Referring to the drawings, the several species of the invention all have in common a driving wheel 10 D driven by a suitable motor such as a conventional spring motor M. The toys further comprise steering means such as a steering wheel S, which is normally biased in one direction. A control cord C extends from the toy upwardly far enough to be held in the hand of a person walking along with the toy. This control string is operatively connected to the steering wheel S in such a manner that a light tension on the string turns the steering wheel away from the biased or normal position, thus changing the direction of movement of the toy. A comparatively small movement of the string is enough to change the direction of the toy, and this movement is relatively unnoticeable to observers watching the operation of the toy. The operation is therefore puzzling to the uninitiated, and this increases the amusement afforded by the toy.

Considering the toys in greater detail, and referring first to the toy automobile shown in Figs. 1 through 4, the toy comprises a body 12 which may be formed of sheet metal in accordance with conventional practice. The driving wheels D may also be made in accordance with conventional practice, these wheels being secured to a suitable axle 14 passing through the frame 16 of a conventional spring motor, said motor comprising the winding stem 18 having a spiral ribbon spring connected thereto. The winding stem is geared to the axle 14 by a conventional train of step-up gearing.

The steering wheels S are freely rotatable on stub axles 20 which in turn project outwardly from king pins 22 received between the top and bottom parts 24 and 26 of an axle housing 28. Arms 30 are secured to and extend rearwardly from the king pins 22, and these arms are connected to one another by a suitable tie bar or cross-link 32. The wheels are steered by oscillation of a vertical spindle 34 which carries an arm 36 the rear end of which is pivotally connected to link 32 at 38. Spindle 34 carries a worm gear 40.

The cord C is connected at its inner end 42 to a drum 44 on which a part of the cord is normally wound. This drum is secured to a

generally horizontal spindle 46 extending longitudinally of the toy. The forward end is journalled at 48, and the rear end on a bracket 50. A worm 52 is carried near the forward end of spindle 46 and meshes with the worm gear 40, thus controlling the steering of the toy. A thin, light spring wire 54 is coiled about shaft 46 and is connected at one end to the drum 44 and at the other end to the vehicle body, as for example, on bracket 56. This spring turns the drum in one direction, thus biassing the steering wheels to the extreme limit of movement on one side. The angle of the steering wheels may be limited by appropriate stops 58 associated with the steering linkage, or, if desired, a bead 60 may be clamped on the string C to limit the inward movement of the string. In the present case a guide tube 62 is provided between the opening in the roof of the auto and the drum, but this is not essential.

It will be understood that the toy is preliminarily energized by winding the motor stem 18 with a suitable key. The toy is then set on the ground and permitted to run, the cord C meanwhile extending upwardly as is indicated by the broken line C'. The cord is held in the hand of a child, who walks along with the toy, and who readily guides or steers the toy in one direction or another by lightly tensioning the cord. The biassing spring 54 is purposely made very light so that it will not interfere with the tractive effort of the driving motor and the normal movement of the toy along the ground.

Inasmuch as a child may wish to dispense with the remote control at times, and inasmuch as the toy would then steer in only one direction, additional means may be provided to fix the steering wheels in any desired position. In the present case, a cleat 64 is formed on one side of the toy, and the string is simply turned about the cleat with the steering wheels pointed as desired, for example, straight ahead. The remainder of the string may be disposed of by simply putting the same inside the toy body through the window 66. In the present case a special spool 68 has been provided, this spool being detachably applied to the toy by pushing a tapered projection 70 on the spool through a mating opening in the toy body, as for example, in the running board. The excess cord is wound about spool 68 and is thus conveniently disposed of.

Referring now to the toy shown in Figs. 5 and 6, the body 70 simulates a Scottie dog. It runs on a pair of rear driving wheels 72 which are substantially concealed by the body. The wheels are mounted on an axle 74 geared in conventional fashion by a train of step-up gearing leading from the winding stem 76 of a conventional spring motor carried in a motor frame 78. It will be understood that a spiral ribbon spring is connected at one end in the usual way to winding stem 76. One plate of the motor frame may be extended forwardly as is indicated at 80 to carry the steering mechanism.

The toy is steered by a single small steering wheel 82 projecting through a circular opening 84 in the bottom 86 of the toy. Wheel 82 is freely rotatable on an axle 88 formed integrally with a vertical steering spindle 90. This is journalled in bearings 92 bent sidewardly from plate 80. Spindle 90 carries a worm gear 94 meshing with a worm 96 carried on a horizontal spindle 98 which also carries drum 100. The spindle 98 is normally biassed or turned in one direction by a light spring wire 102, one end of which is

secured to the drum at 104, and the other end of which is secured to the motor frame at 106. The inner end of the control cord C is, of course, secured to the drum just as was previously described, and a part of the cord is wound on the drum by the biassing action of spring 102. The cord passes through appropriate guide eyelets 108 and 110, the latter preferably being so located that the cord will simulate a leash extending from the neck of the animal. To heighten this illusion, a simulated collar may be provided, or the toy may be painted to simulate a collar, this being indicated by the dotted lines 112.

If desired, the action of the toy may be increased by making the head 114 movable. In the present case, the head is made separately from the body, and is mounted at the upper end of spindle 90, as is indicated at 116. To this end the surfaces 118 separating the head and body are made perpendicular to spindle 90, and are preferably made circular in outline, so that the head and body will fit accurately together even though the head is turned in one direction or another. It will be understood that in operation, the toy runs along somewhat ahead of the child, the latter holding the cord or leash. The toy is steered erratically in one direction or another, depending upon the tension applied to the cord by the child. The head turns and looks in the direction in which the toy is steered. For very small children, the string may be marked to aid steering, as by a center mark 115. End marks 117 and 119 may also be used. The mark 117 may be a bead for motion-limiting purposes.

If desired, further action may be given to the toy by oscillating a part thereof under drive of the motor M. In the present case the toy is provided with a tail 120 oscillatably mounted at 122 and having a cam follower 124 connected thereto. The cam follower cooperates with a cylindrical cam 126 mounted on a shaft 128 and geared to the driving train of motor M by means of any suitable intermediate gearing. In this way the tail is caused to wag back and forth as the toy runs along.

Coming now to the toy illustrated in Figs. 7, 8 and 9, this toy simulates an automobile equipped with a radio antenna. The body 130 may be of generally conventional type. The rear wheels D are conventional driving wheels geared in the usual manner to a spring driving motor the winding stem of which is indicated at 132. The front wheels 134 are mounted on stub axles 136 carried on and oscillatable about king pins 138. Steering arms 140 extend forwardly from the king pins and are connected by a vertically disposed plate 142 acting as a tie bar or cross link. This plate has three upstanding fingers or pins, the end fingers 144 passing upwardly through holes in arms 140, and the center finger 146 passing upwardly through a hole in a bell crank lever 148. This lever is pivoted at 150, and has a sidewardly and then upwardly extending arm 152 to which the forward end of a wire link 154 is connected.

The simulated radio antenna 156 is pivoted at 158, and this forms a bell crank lever the other arm 160 of which projects downwardly inside the toy body. The rear end of link 154 is connected to arm 160. The arm is normally biassed to forward position by a light biassing spring 162. In this way the wheels are normally turned toward one side, and the antenna normally assumes the broken line position 156'. The control string C is tied to the rear end of antenna 156.

156 at eye 164. It will be understood that the string extends upwardly and is held by the child, who walks along with the toy, all as previously described. A slight movement of the string upwardly or downwardly changes the steering of the toy and causes the same to run in any desired direction.

10 It is believed that the mode of constructing and using, as well as the many advantages of the invention, will be apparent from the foregoing detailed description thereof. It will also be apparent that while we have shown and described the invention in several preferred forms, many changes and modifications may be made in the 15 structures disclosed, without departing from the spirit of the invention defined in the following claims.

We claim:

1. A wheeled toy comprising steering means, means normally lightly biasing the steering means in one direction, a non-resilient, highly flexible fibrous string extending from the toy, said string being operatively connected to said steering means in such manner that pull tension applied 25 to the string turns the steering means in the opposite direction.

2. A self-propelled wheeled toy comprising a driving wheel, a motor geared to said driving wheel, steering means, means normally lightly biasing the steering means in one direction, a non-resilient, highly flexible fibrous string extending from the toy, said string being operatively connected to said steering means in such manner that pull tension applied to the string turns the steering means in the opposite direction.

3. A self-propelled wheeled toy comprising a driving wheel, a spring motor geared to said driving wheel, a steering wheel, resilient means normally lightly biasing the steering wheel in one direction, a non-resilient, highly flexible fibrous string extending from the toy far enough to be held in the hand of a person walking along with the toy, said string being operatively connected 45 to said steering means in such manner that pull tension applied to the string turns the steering means in the opposite direction against the resilient means.

4. A wheeled toy comprising a steering wheel, 50 a drum, a string extending from said drum, light resilient means for turning the drum in one direction in order to wind a part of the string onto the drum, and gearing connected between said drum and said steering wheel, whereby said 55 wheel is normally biased in one direction but may be turned in the other direction by a light pull on the string.

5. A self-propelled wheeled toy comprising a driving wheel, a motor geared thereto, a steering 60 wheel, a drum, a string extending from said drum, light resilient means for turning the drum in one direction in order to wind a part of the string onto the drum, gearing connected between said drum and said steering wheel, whereby said wheel 65 is normally biased in one direction but may be turned in the other direction by a light pull on the string.

6. A self-propelled wheeled toy comprising a 70 pair of driving wheels, a spring motor geared thereto, a steering wheel, a drum, a string extending from said drum far enough to be held in the hand of a person walking along with said toy, light resilient means for turning the drum in one direction in order to wind a part of the string 75 onto the drum, mechanism including a worm and

gear connected between said drum and said steering wheel, whereby said wheel is normally biased in one direction but may be turned in the other direction by a light pull on the string.

7. A self-propelled wheeled toy comprising a 5 driving wheel, a motor geared to said driving wheel, a steering wheel, means normally lightly biasing the steering means in one direction, a non-resilient, highly flexible fibrous string extending from the toy far enough to be held in 10 the hand of a person walking along with the toy, said string being operatively connected to said steering means in such manner that pull tension applied to the string turns the steering means in the opposite direction, and optionally usable 15 means to fix the steering means in any desired direction.

8. A wheeled toy comprising a steering wheel, a drum, a non-resilient, highly flexible fibrous string extending from said drum far enough to be held in 20 the hand of a person walking along with said toy, light resilient means for turning the drum in one direction in order to wind a part of the string onto the drum, gearing connected between said drum and said wheel whereby said 25 wheel is normally biased in one direction but may be turned in the other direction by a light pull on the string, and optionally usable means to fix the wheel in any desired steering position.

9. A self-propelled wheeled toy comprising a 30 toy body, a pair of rear driving wheels, a motor geared thereto, a steering wheel, a drum rotatably mounted in the toy, a string extending from said drum far enough to be held in the hand of a person walking along with said toy, light resilient 35 means for turning the drum in one direction in order to wind a part of the string onto the drum, gearing connected between said drum and said front wheel whereby said wheel is normally biased in one direction but may be turned in the other 40 direction by a light pull on the string, and means on the toy body by which the string may be secured in partially unwound position in order to hold the front wheel in any desired steering position.

10. A self-propelled wheeled toy comprising a 45 toy body simulating an automobile, a pair of rear driving wheels, a pair of front steering wheels, a drum rotatably mounted with its axis extending longitudinally of the toy, a string extending from said drum through the top of the toy far enough to be held in the hand of a person walking along with said toy, light resilient means for turning the drum in one direction in order to wind a part 50 of the string onto the drum, mechanism including a worm and gear connected between said drum and said front wheels whereby said wheels are normally biased in one direction but may be turned in the other direction by a light pull on the 55 string, and a spool mounted on the toy on which the string may be wound when the string is not being used for remote control.

11. A self-propelled wheeled toy comprising a 65 body simulating an animal, a driving wheel, a motor geared thereto, a steering wheel, a non-resilient, highly flexible fibrous string simulating a leash extending far enough to be held in the hand of a person walking along with said toy, light resilient means for turning the steering 70 wheel in one direction, means connecting the string and steering wheel for steering it in the opposite direction whereby said wheel is normally biased in one direction but may be turned in the other direction by a light pull on the string.

12. A self-propelled wheeled toy comprising a body simulating an animal, a driving wheel, a motor geared thereto, a steering wheel, a drum, a string simulating a leash extending from said drum far enough to be held in the hand of a person walking along with said toy, light resilient means for turning the drum in one direction in order to wind a part of the string onto the drum, gearing between said drum and said steering wheel, whereby said wheel is normally biased in one direction but may be turned in the other direction by a light pull on the string. 5
13. A self-propelled wheeled toy comprising a body simulating an animal, a pair of driving wheels, a spring motor geared thereto, the head of said animal being pivotally related to the body of the animal, a steering wheel, means operatively connecting the steering wheel and the head so that the head is turned when the steering wheel is turned, a drum, a string extending from said drum, light resilient means for turning the drum in one direction in order to wind a part of the string onto the drum, gearing between said drum and said steering wheel, whereby said wheel is normally biased in one direction but may be turned in the other direction by a light pull on the string. 10
14. A self-propelled wheeled toy comprising a body simulating an animal, a pair of driving wheels, a spring motor geared thereto, a part of said toy body movably mounted thereon and connected to the spring motor for movement thereby, a steering wheel, a drum, a string simulating a leash extending from said drum far enough to be held in the hand of a person walking along with said toy, light resilient means for turning the drum in one direction in order to wind a part of the string onto the drum, gearing between said drum and said steering wheel, whereby said wheel is normally biased in one direction but may be turned in the other direction by a light pull on the string. 15
15. A self-propelled wheeled toy comprising a body simulating a dog, a pair of driving wheels, a spring motor geared thereto, the head of said dog being pivotally related to the body of the dog, a steering wheel, means operatively connecting the steering wheel and the head so that the head is turned when the steering wheel is turned, a drum, a string simulating a leash extending from said drum far enough to be held in the hand of a person walking along with said toy, light re- 20
- silient means for turning the drum in one direction in order to wind a part of the string onto the drum, mechanism between said drum and said steering wheel, whereby said wheel is normally biased in one direction but may be turned in the other direction by a light pull on the string. 25
16. A self-propelled wheeled toy comprising a toy body, a driving wheel, a motor geared to said driving wheel, a steering wheel, means pivotally mounted on the toy to act as a steering control lever, linkage connecting the inner end of said lever to the steering wheel, light resilient means normally biasing the steering wheel and lever in one direction, and a non-resilient, highly flexible fibrous control string attached to the end of the lever, whereby pull tension on said string turns the steering wheel in the opposite direction. 30
17. A self-propelled wheeled toy comprising a toy body having a simulated radio antenna, a driving wheel, a motor geared to said driving wheel, steering means, means pivotally mounting the simulated antenna on the toy to act as a steering control lever, linkage connecting the inner end of said lever to the steering means, means normally biasing the steering means and antenna in one direction, and a non-resilient, highly flexible fibrous control string attached to the end of the antenna and extending upwardly far enough to be held in the hand of a person walking along with the toy, whereby pull tension on said string turns the steering means in the opposite direction. 35
18. A self-propelled wheeled toy comprising a toy body simulating an automobile having a simulated radio antenna extending over the roof thereof, a driving wheel, a spring motor geared to said driving wheel, a steering wheel, means pivotally mounting the simulated antenna on the toy to act as a steering control lever, linkage within the toy connecting the inner end of said lever to the steering wheel, light resilient means normally biasing the steering wheel in one direction and moving the antenna to a position directly overlying the roof of the toy, and a non-resilient, highly flexible fibrous control string attached to the end of the antenna and extending upwardly far enough to be held in the hand of a person walking along with the toy, whereby pull tension on said string turns the steering wheel in the opposite direction. 40
